UNITED STATES PATENT OFFICE.

LORENZO STEBBINS, OF HINSDALE, NEW HAMPSHIRE, AND GEORGE P. STEBBINS, OF VERNON, VERMONT.

CAR-COUPING.

SPECIFICATION forming part of Letters Patent No. 308,103, dated November 18, 1884.

Application filed September 25, 1884. (No model.)

To all whom it may concern:

Be it known that we, LORENZO STEBBINS, of Hinsdale, in the county of Cheshire, State of New Hampshire, and GEORGE P. STEBBINS, of Vernon, in the county of Windham, State of Vermont, have invented a new and Improved Car-Coupling, of which the following is a specification.

Our invention is designed to produce a coupler that is automatic in coupling, and having a link always ready for use, and though capable of removal, if desired, it is intended to always remain in the head of the draw-bar when uncoupled as when coupled.

In the accompanying drawings of a car-coupling embodying our invention, Figure 1 is a plan of the coupling with a convenient arrangement for uncoupling from either side or top of the car. Fig. 2 is a side view of the same and the mouth, link, and hook of another coupling, shown in broken lines as when coupled for use. Fig. 3 is a front or end view of the head and hook-pin, as seen from the right of Fig. 1. Figs. 4 and 5 are two views of the link.

The same letters indicate the same part in all.

A is the head of the draw-bar A², made with the usual form of flaring mouth, and having a cavity enlarged laterally inside, as shown by the broken line A', Fig. 1, and its bottom sloping down from the mouth, as shown in Fig. 2.

C is the link, made in the form shown in Figs. 4 and 5, heavy at one end and spread wider than the opening in the head A, so that it cannot be drawn out, though the pin B is out, without being turned up sidewise or on edge, in which position it can be removed or put into the head A. The end C' of the link is more of the common rounded form, but made with an edge, as shown, so that in coming together the links, though hitting each other, pass readily the one over the other, as in Fig. 2, the under one making the connection and coupling.

As in some cases it may be desired to use our coupling with another requiring one of the old crooked links, we make an opening 50 through its back above the bar, to which the head is attached, so that by raising the link to

the top of the cavity in the head it may be slid back, as shown at C⁴, Fig. 2, until the front end of the link is even with the front edge or mouth of the head, so that our coupling can be used when necessary with the old common forms of heads and links. The pin B has a long body, and is designed to remain always in the broad end of the link, as in Figs. 1 and 2, and has a coupling-hook attached to it in front. Said hook (shown at B', Figs. 1, 2, and 3) is made of the form shown, its sloping under surface enabling the link of the other coupling to raise the whole pin and pass beyond the point of the hook, which falls and makes the connection or couples, its upper slope allowing the top link to slide up and rest thereon, as shown in Fig. 2. Thus it is immaterial which link in coming together passes over the other. The under one is guided by the upper, so as to pass under the hook and raise it and complete the connection. The upper part of the pin B is made wider than the hook and lower part, so as to bear on each side on the ribs b b for strength. The wide-spread form of the broad end C² of the link gives the necessary lateral play on the pin for curves, &c.

The arrangement and connections shown for raising the pin B or uncoupling are provided with means for holding said pin up for "kicking," as when raised by the rod c from the top of the car the rod turned slightly will bring the pin c' so as to rest in the catch c², or when the pin B is raised from the side by the lever d² the lug e, which is pivoted on the car D at e', can be turned to the position shown in broken lines, and its arm e² receive and support the lever d², holding up the pin uncoupled when backing, when so desired. The heavy end c² of the link when not coupled rests always on the inclined bottom of the head, raising the outer end slightly, so as to be always ready for coupling, and can be used with the old or common form of head and pin, if desired.

The lower end of the pin B² can be protected by a guard from the edge of the mouth, if desirable.

We claim—

1. The coupling described, consisting of the flaring-mouthed head having a cavity laterally

widened interiorly, and a pin provided with a hook, as described, in combination with a link made with a laterally-spread rear end and cavity, through which the pin passes, substantially as and for the purposes described.

5 2. The combination of the head having an interiorly laterally-widened cavity with a sloping bottom, as described, the pin having a

hook, and the link made with a spread heavy rear end, as above set forth.

LORENZO STEBBINS.
